READY TRANSFER REEL

Robert M. Vadas, Montreal, Quebec, and Adu Randpalu, La Salle, Quebec, Canada, assignors to Dominion Engineering Works Limited, Lachine, Quebec, Canada, a corporation of Canada

Filed Oct. 20, 1966, Ser. No. 588,153
8 Claims. (Cl. 242—65)

This invention is directed to a reel bar transfer arrangement, and in particular to an arrangement of reel bar support frames for use with a reel drum of a paper reeling machine.

In the manufacture of paper which is generally a continuous flow process it is necessary to provide a spool or reel bar on which the continuously moving sheet of paper can be rolled for subsequent handling and re-rolling. Owing to the large lengths of paper involved the diameter and mass of rolled paper increases at a rapid rate, and in order to facilitate control of the tension of the paper it is usual to move the growing roll from an initial reeling position above the reel drum to a secondary position beside the reel drum, where the weight of the paper and reel bar is rendered substantially ineffective.

In the secondary position a fluid actuator provides a transverse force against the bearings of the reel bar to maintain the desired nip pressure to provide constant tension on the paper.

In operation and especially at a start-up of the paper machine, it sometimes happens that the first quantity of paper on the roll may not be of the required quality in which case continuance of reeling onto that roll will result in a large quantity of spoilage. Previous arrangements of reel transfer arms provide a retaining arm fixedly mounted on each primary arm and extending parallel therewith to form a bight portion or U extending upwardly, with the primary arm in the initial upright position. On movement of the reel bar support frame downwardly into the horizontal position, with the reel bar supported upon the secondary tracks provided for that purpose it is still not possible to withdraw the primary support arm means to the desired initial position, until such time as the paper reel increases in diameter to a sufficient extent to displace the reel bar bearing past its point of contact with the retaining arm.

In prior attempts to overcome the drawbacks inherent in such a retaining arm structure, means have been provided to retract the retaining arm constituting one upright leg of the retaining U section, in a direction radially inward along the primary arm towards the common axis with the reel drum, but such prior efforts have not been very successful, and have not provided reel bar primary arm means that can be readily and rapidly moved from the secondary or horizontal position back to the primary or upright position while at the same time maintaining an effective nip with the reel drum.

The present invention provides reel bar retaining means mounted on reel bar support frames to provide continuous reeling in positions ranging from the primary vertical position to the secondary horizontal position, while at the same time being capable of withdrawal from the secondary position to the primary position, thus permitting the relinquished reel bar to continue reeling in the secondary position. Thus, a second reel bar can be placed above the reel drum in secured relation with the end frames, while the first reel bar continues winding of the paper web. When the quality or quantity of paper wound on the reel is such that a change of reel bar is required, operation of an air jet provides severance and upward deflection of the paper web, to commence reeling on the second reel mounted in the primary posi-

2

tion, while the first reel can then be removed from the secondary position without interrupting the winding process.

What has been provided, in a reel bar transfer arrangement for use with a reeling machine having a reel drum rotatable about the main axis thereof, with a pair of reel bar support frames positioned adjacent the ends of said drum in cooperative reel bar supporting arrangement to move a said reel bar between a first, substantially upright loading position and a second, substantially horizontal withdrawal position, is a pair of support frames, each comprising: a primary frame portion pivotably mountable adjacent said reel drum for angular movement relative thereto in a plane normal to the drum main axis, having a fixed reel bar contact surface located in a downward facing direction when the frame is in the second position, to permit unrestricted withdrawal of the primary frame from a reel bar bearing on moving in the direction from the frame second position towards the frame first position; and reel bar bearing keep means mounted on the frame portion for movement relative thereto from a closed position overlying a portion of the reel bar bearing, in which the reel bar bearing is secured to the frame by contact of the keep means against an outer portion of the bearing remote from the fixed contact surface, to an open position in which the reel bar bearing may be loaded on or off the frame, or the frame may be substantially freely withdrawn from the reel bar bearing by withdrawal movement in the direction from the frame second position to the frame first position, whereby withdrawal movement of the support frame may be effected independently of the wound condition of the reel bar.

An embodiment of the present invention is described by way of example, reference being had to the accompanying drawings, wherein:

FIGURE 1 is a front perspective view of a paper reeling arrangement embodying reel bar retaining means according to the present invention;

FIGURE 2 is a side view in part section taken in the direction 2—2 of FIGURE 1; and

FIGURE 3 is a side view corresponding to FIG. 2 showing a reel in an intermediate position.

Referring first to FIGURES 2 and 3, the reel drum 15 rotatably mounted in end bearings 16 and rotatably driven by a means not shown receives a paper web 17 passing under a guide roll 18. A reel bar 19 mounted in reel bar support frame means 20 is initially located above the reel drum 15, being secured to the primary arm means 21 of the reel bar support frame 20 by the bearing keep means 28.

The reel bar 19 is initially supported clear of the reel drum 15, being mounted on a reel bar support pedestal 42 which has a substantially horizontal support face 43 receiving the bearing housing of the reel bar. When the reel bar 19 has been brought up to winding speed by an auxiliary belt, horizontal movement rearwardly, in an anti-clockwise direction as seen in FIGURE 2, brings the periphery of the reel bar 19 into driven contact with the periphery of the reel drum 15, so that the paper web 17 passing therebetween can be wound onto the reel bar 19 and is then continuously wound at a substantially constant tension. Initially tension is provided partly by the weight of the reel bar and partly by cylinder 37 of bearing keep means 28. The support frames 20 are then moved anti-clockwise until a horizontal position is reached, at which time the load of the reel bar 19 is taken by secondary tracks 55, while the desired radially inward loading necessary to maintain reeling contact between the reel bar and the reel drum is provided by secondary loading means 56. When this condition is reached, the bearing keep means 28 can then be freely withdrawn from securing re-

lation with the bearings of the reel bar 19, thus permitting the support frame primary arm means 21 to be rotated clockwise from the horizontal secondary to the vertical primary position. When the primary position is again reached it is then possible to mount a second reel bar 19 on the support pedestals 42 in secured relation with the primary arm means 21. Actuation of an air jet (not shown) to sever the paper web from the first reel bar 19, now mounted on the secondary tracks 55, permits reeling of the continuously moving web 17 to be continued on the second reel bar, when that bar has been brought up to speed by an auxiliary belt drive, by moving the second reel bar off the pedestal 42 into reeling contact with the reel drum 15, the paper web 17 being blown upwardly by the air blast to encircle the second rotating reel bar 19.

The reel bar support frame means 20 comprises a primary arm 21 having a pivotal bearing housing 22 at one end and a recess 23 at the outer end. A bearing contact surface 26 provides an elongated surface along which the bearing housing of the reel bar 19 can move in a downward loading direction, as the reel is initially lowered into the primary reeling position, the bearing keep means 28 being retracted upwardly into housing recess 23.

The bearing keep means 28 includes an arm member 29 pivotally mounted on a pivot 30 secured to the primary arm means 21, and having a hook portion 31 at the outer end thereof. A steady roller 32 mounted on the arm 29 serves to locate the reel bar bearing housing, and applies primary loading to the reel bar, in conjunction with a portion of the hook 31.

The keep means 28 is controllably positioned by means of a keep actuator 35 connected thereto by an actuator pin 33. The actuator 36 comprises a cylinder 37 having an end pivotal mount 38; a piston 39 extending therefrom, the outer end 40 thereof being secured to the pin 33 attached to the arm 29.

A pressure limiting valve in the control circuit of the actuator 36 permits the keep means 28 to back-off as the reel grows in diameter, thus moving the reel bar 19 radially outwardly in relation to the reel drum.

It will be seen that operation of the keep actuator produces pivoting of the bearing keep arm about the pivot 30 to provide engagement or disengagement with a reel bar bearing housing.

The primary arm 21 is pivotally positioned by means of a primary arm actuator 45 having a cylinder 46 and a piston 47 with the ends thereof pivotally mounted at 48 and 49 respectively, the piston 47 being connected with a bell disc 21', connected to the primary arm 21.

In the initial position of a reel bar 19, the bar is vertically supported upon the pedestal 42, in conjunction with the bearing keep means 28 which retains the reel bar bearing housing secured in locked relation with the primary arm 21. Anti-clockwise movement of the primary arm 21, on actuation of the actuator 45, produces driving contact between the outer periphery of the reel drum 15 and the outer periphery of the reel bar 19, the paper web 17 passing between the nip so formed. Continued operation of the primary arm actuator 45 results ultimately in the positioning of the reel bar 19 in supported relation upon the secondary tracks 55, at which time the bearing keep means 28 can be retracted by operation of the keep actuator 36 to the open position, in which condition the primary arm 21 may then be freely rotated clockwise to the upright primary position, thus permitting a second reel bar 19 to be mounted upon the support pedestal 42 for a repetition of the reeling cycle.

The reeling cycle can meanwhile continue with the first reel bar 19 now moving horizontally on the secondary tracks 55 under transverse control of the secondary loading means 56, as the size of the reel grows.

The descent of a reel bar 19 from the primary or top position to the horizontal or secondary position relative to the reel drum 15 is effected by the primary arm actuator 45 acting on bell disc 21'.

A particular advantage afforded by the present invention is that false starts, when the paper web is unduly wet or any other unsatisfactory condition, may be readily accommodated without interrupting the operation of the paper machine, while at the same time being limited in minimum time duration only by the rate at which the primary arm means can be moved from the primary position to the secondary position, the bearing keep means 28 retracted, and the primary arm means moved back to the primary position, as compared with former practice wherein a large quantity of paper had to be wound on the first reel bar 19 before the primary arm means 21 could be withdrawn to the starting position to permit a fresh start.

15 The present invention provides a fail-safe reel transfer arrangement by the provision of hook portions 31 which each constitute an over-centre retaining abutment for rolls of normal wound size.

In the event of depressurization of the keep actuator 20 36, the reel bearing housing is retained within the hook portions 31, owing to the geometry of the arrangement, regardless of the angular position of the frame means 20 about the reel drum axis, intermediate the primary and secondary position.

25 The roll member 32 rotatably mounted on the hook 28, and bearing against the bearing housing in substantially opposing relation to the hook portion 31, provides a component of primary force for the creation of desired nip pressure, while serving to maintain the bearing housing clear of rubbing engagement with the guideway 26.

Synchronization of the operation of the pair of reel arms 20 is provided by a pair of gears interconnected by a lay-shaft (not shown), each being in respective meshing engagement with the bell discs 21', serving as gear 35 quadrants. Substitution of a rotary drive to the interconnecting shaft or to one of the synchronizing gears, in place of the linear actuator 45 is contemplated.

It will be noted that the reel bar support arm primary frames are freely rotatable upwardly for withdrawal from 40 engagement with a reel bar supported on the secondary tracks, substantially independently of the presence or absence of paper wound on the reel bar.

What we claim as new and desire to secure by Letters Patent of the United States is:

45 1. A reel bar support frame, for use in a reeling machine having a reel drum rotatable about the main axis thereof and a pair of said support frames positioned adjacent the ends of said drum in cooperative reel bar supporting arrangement to move a said reel bar between a first substantially upright loading position and a second substantially horizontal withdrawal position, each frame comprising: a primary frame portion pivotally mountable adjacent said reel drum for angular movement relative thereto in a plane normal to said main axis, having a fixed reel bar contact surface located in a downward facing direction when the frame is in said second position, to permit unrestricted withdrawal of the frame from a said reel bar bearing on moving in the direction from said frame second position towards said frame first position; and reel bar bearing keep means mounted on the primary frame portion for movement relative thereto from a closed position overlying a portion of said reel bar bearing, in which said reel bar bearing is secured to the frame by contact of the keep means against an outer portion of the bearing remote from said fixed contact surface, to an open position in which said reel bar bearing may be loaded on or off the frame, or the frame may be substantially freely withdrawn from said reel bar bearing by withdrawal movement in the direction from the frame second position to the frame first position, whereby withdrawal movement of the support frame may be effected independently of the wound condition of the reel bar.

70 2. A reel bar support frame as claimed in claim 1 including means for moving said bearing keep means rela-

tive to said primary frame portion, to permit relative movement of a reel bar bearing in response to growth in the diameter of the reel bar wound outer surface.

3. A reel bar support frame as claimed in claim 2 wherein said keep means includes a support arm pivotally mounted on said primary frame portion, having a hook portion extending from the support arm in the direction of the reel drum when in the closed position to control tangential and radially outward movement of a said reel bar relative to said primary frame portion, being arranged in a substantially fail-safe relationship to preclude dropping of a said reel bar.

4. A reel bar support frame as claimed in claim 2 wherein said means for moving said bearing keep means relative to said primary arm means includes a fluid operated actuator providing angular movement of said bearing keep means relative to the primary arm means, and including pressure relief means permitting radially outward movement of the reel bar bearing relative to the reel drum, whereby the effective diameter of material wound upon the reel bar is permitted to increase.

5. A reel bar support frame as claimed in claim 1, including actuator means in driving relation with said primary frame portion to provide rotation thereof relative to said reel drum, whereby a said reel bar may be selectively moved from said first position, above the reel drum to said secondary position in substantially horizontal relationship with the reel drum.

6. A pair of reel bar support frames as claimed in claim 1, in combination with a reeling machine having a pair of pedestals with substantially horizontal reel bar support faces positioned above and towards the oncoming side of the reel drum axis, to permit positioning of a reel bar in a winding position above the reel drum and out of winding contact therewith, the disposition of the support faces relative to the drum and bar being such that rearward displacement of the bar by said support frame brings the bar into driven contact with the surface of the drum.

7. A reel support frame as claimed in claim 1, including roller steady means rotatably mounted on said bearing keep means in substantially opposing relation to the outer contact portion of said keep means, to provide a primary, radially inward nip loading force against a reel bar bearing mounted therein, said outer contact keep portion serving

to positively secure a said reel bar bearing in supported relation with said reel support frame, in fail-safe relation.

8. A reeling machine, comprising: a reel drum rotatable about the main axis thereof; a pair of reel bar support frames mounted for pivotal movement relative thereto in planes adjacent the ends of said drum and normal to said main axis, each frame including a pivotally mounted primary frame portion having a fixed reel bar contact surface located in a downward facing direction when the frame is in a horizontal position permitting unrestricted withdrawal of the frame from a said reel bar on moving the frame upwardly therefrom, and reel bar bearing keep means pivotally mounted on the primary frame portion for movement relative thereto from a closed position overlying a portion of said reel bar bearing in which said reel bar bearing is secured to the primary frame portion by contact of a hook portion of the keep means against an outer portion of the bearing remote from said fixed contact surface, to an open position in which said reel bar bearing may be loaded on or off the frame may be substantially freely withdrawn from said reel bar bearing by upward withdrawal movement therefrom towards an upright frame position; a fluid operated actuator mounted on each said primary frame for pivoting the respective keep means relative to the respective primary frame portion; a second actuator for positioning said frames about said reel drum in cooperation with a synchronizing means interconnecting said pair of frames to provide synchronized angular positioning of said frames relative to the reel drum; pedestal means for supporting a said reel bar above said reel drum; reel bar drive means for accelerating a said reel bar into related rotation with said reel drum; and secondary track means to receive a said reel bar when released from said support frames, whereby reeling of paper may be maintained while said reel bar support frames are repositioned to an upright position to receive a further reel bar.
